UNITED STATES PATENT OFFICE.

JOSEPH W. DUBRAKS, OF HOUSTON, TEXAS.

REFRIGERATING APPARATUS.

Application filed December 26, 1924. Serial No. 758,126.

To all whom it may concern:

Be it known that I, JOSEPH W. DUBRAKS, a citizen of the United States, residing at 1601 Alamo Street, Houston, Texas, have invented a certain new and useful Improvement in Refrigerating Apparatus, of which the following is a specification.

My invention relates to devices for maintaining low temperatures in closed vessels for the freezing and storage of confections and frozen foods.

It is an object of the invention to provide a refrigerating chamber wherein the temperatures may be kept near freezing in a most economical manner. It is also desired that the apparatus be adapted to provide a plurality of chambers all of which may be maintained at low temperatures and yet readily accessible when it is desired that they be removed.

Referring to the drawing herewith, Fig. 1 is a central vertical section of a refrigerator embodying my invention. Fig. 2 is a perspective view of one of the removable compartments. Fig. 3 is a top view in section approximately on the plane 3-3 of Fig. 1. Fig. 4 is a top plan view with the top closed. Like numerals of reference are employed to designate like parts in all the views.

In constructing the device, I employ an outer tub or container 1 which may be wood or sheet metal and I have shown a cylindrical sheet metal tub with a circular bottom 2 of wood.

Within the tub is an inner sheet metal container 3, the bottom and sides of which are spaced about equal distances from the inner face of the tub thus providing a chamber 4 between the two containers which I contemplate filling with some good heat insulating material such as cork 5 preferably granulated. The upper ends of the two containers are spaced apart, and the chamber between them closed, by an annular closure 6 secured firmly to the wall of the outer tub.

The upper end of the inner container projects above the closure 6 and has thereon a ring 7 forming a rim overlapping the lower ring.

Above the ring 7 is a cover made up of two stationary segmental side pieces 8 between the spaced ends of which are supporting plates 9, 9, somewhat narrower in width than the side pieces. To these sup-

ports 9, 9 are hinged the doors 10, 10 shaped to close the open end of the container and meeting along a diametrical line 11. Handles 12 are provided for opening the doors 60 when desired.

Within the container 3, and spaced therefrom, is an upright concentric wall 13, spaced from the container by a plurality of radial partitions 14, provided with openings 65 15 therein for purposes of air circulation.

It is also contemplated that an inner can or container 16 of sheet metal will be provided, materially smaller than the chamber 17 in which it is seated. The chamber 17 70 will permit a receptacle for ice 18, or other refrigerating means. The container 16 will be fitted with a cover 19 thereon.

The separate compartments between the various radial walls 14 furnish storage for 75 a series of holding trays or containers 20 of the form shown in Fig. 2. The said trays are segmental in shape to fit the said compartments. They have openings 21 adapted to register with the openings 15 in 80 the partitions 14 and the inner wall is cut away from a point adjacent the lower end to the upper end. The top is closed and formed with a handle 22. A hooked flange 23 engages over the upper edge of the wall 85 13 to support the tray with the lower end thereof slightly off the bottom.

A drain pipe 24 extending through the walls from the ice chamber outwardly acts to conduct liquid from the container to the 90 outside. Opposite curved rods 25, on each side to the rear of the doors act as supports for the doors when open, as illustrated in Fig. 1.

The device thus constructed will serve as 95 a freezer when the ice 18 is mixed with salt; and simply as a refrigerator when the salt is omitted. It will be noted that there are refrigerating compartments outside the ice chamber as well as inside the same. The 100 same ice chamber is thus adapted to exert a refrigerating effect in both directions, thereby effecting a great economy. It has been found that the outer wall of the container 1 is not noticeably cooled in this arrangement 105 and will not gather moisture in warm weather, as ordinary metal refrigerators now sometimes do. It is contemplated that the trays may be employed to hold frozen dainties and confections for storage purposes and for sale. When thus used, the desired tray may be elevated to expose the 110

packages of confection desired and then the tray may be again replaced and the refrigerator closed. Obviously the central chamber 16 is also easily accessible and may contain ice cream, ices of various kinds or may be also used for storage of packages of dainties which must be kept cold, bottles containing various drinks or other similar materials ordinarily dispensed at confectionery stores.

It has been found that such a device is exceedingly efficient in operation and economical in the use of ice, and will maintain low temperature for comparatively long periods.

Having thus described the invention, what I claim as new and desire to protect by Letters Patent is:

1. A refrigerating device comprising an outer tub, a cover thereon, a container in said tub, heat insulating material between said tub and container, an annular ice chamber spaced within said container, radial compartments between said ice chamber and said container, and a storage compartment surrounded by said ice chamber.

2. A refrigerating device comprising an outer container having a wall of heat insulating material around the same, a central

storage container, an annular refrigerating chamber surrounding said storage container and a series of compartments between said refrigerating chamber and said outer container.

3. A device of the character described comprising spaced inner and outer concentric storage chambers with an intermediate annular refrigerating chamber between them, heat-insulated walls for said outer storage chamber, and removable compartments in said outer storage chamber having upper hooked supports thereon, said compartments being perforated to allow air circulation therethrough.

4. A device of the character described comprising an inner storage container, a second storage container outside of and concentric with the inner container, a refrigerating chamber between said containers, heat insulating walls surrounding said containers, and separately removable compartments in said second storage chamber.

In testimony whereof I hereunto affix my signature this 20th day of December, A. D. 1924.

JOSEPH W. DUBRAKS.
